ADJUSTABLE SPINDLE FOR SUPPORTING CLOTH ROLLS

Jules Nisenzon, Rye, N.Y., assignor to Cutting Room Appliances Corp., New York, N.Y., a corporation of New York

Filed May 25, 1962, Ser. No. 197,736
2 Claims. (Cl. 242—72)

This invention relates generally to the field of roll-supporting spindles, and more particularly to an improved form thereof in which the effective outer diameter is radially expandable, much in the manner of an adjustable-diameter mandrel. While the invention has applications in many fields, it is particularly suitable for use as a cloth roll support of a type widely used in cloth laying devices adapted to transversely move over a cloth laying table to deposit successive layers of cloth prior to cutting of the same.

In devices of this type, it is desirable that the cloth be laid in an even manner, in which the edges of each successive layer will coincide with those of layers disposed immediately therebeneath. Where the roll of cloth supported by the carriage of such a device is of a diameter other than the internal diameter of the roll, a certain amount of movement about an axis perpendicular to that of the axis of rotation will occur as rotation progresses, resulting in the dispensing of cloth from the roll in a direction other than exactly normal to the axis of rotation of the spindle. This will result in uneven cloth distribution as the web of cloth proceeds past the cloth distributing rollers.

It is therefore among the principal objects of the present invention to provide a spindle of the class described in which the effective outer diameter thereof is adjustable to accommodate varying internal diameters of cloth rolls.

Another object of the invention lies in the provision of an improved adjustable spindle in which the adjustment may be performed after the cloth roll has been engaged thereupon, thereby facilitating the initial placement of the roll upon the spindle when the effective external diameter is of lesser value, and the subsequent expansion of the spindle to engage the inner surface of the same.

Still another object of the invention lies in the provision of an expandable spindle of the type described in which the expanding portions thereof include a resilient component, whereby the adjustment of the spindle with respect to the cloth roll need not be critical.

Yet a further object of the invention lies in the provision of an improved adjustable spindle possessed of the above advantages, in which the cost of fabrication may be of a reasonably low order, with consequent wide sale, distribution and use.

A feature of the invention lies in the fact that adjustment of the spindle is a simple manual operation, not requiring the use of tools.

These objects and features, as well as other incidental ends and advantages, will more fully appear in the progress of the following disclosure, and be pointed out in the appended claims.

In the drawing, to which reference will be made in the specification, similar reference characters have been employed to designate corresponding parts throughout the several views.

FIGURE 1 is a fragmentary view in elevation, partly in section, of an embodiment of the invention.

FIGURE 2 is a fragmentary enlarged central longitudinal sectional view, partly broken away to show detail, corresponding to the right-hand portion of FIGURE 1.

FIGURE 3 is an enlarged fragmentary central longitudinal sectional view showing one of the adjustable collet elements comprising a part of the embodiment.

2

FIGURE 4 is a transverse sectional view as seen from the plane 4—4 in FIGURE 1.

In accordance with the invention, the device, generally indicated by reference character 10, comprises: an outer tube element 11, an inner tube element 12, a threaded stud element 13, a plurality of movable collet elements 14, a plurality of fixed collet elements 15, a plurality of elongated spring members 16, and a sleeve element 17.

The outer tube element 11 may be formed of any suitable metallic material, preferably a material including the qualities of relatively high strength and relatively low weight. It is cylindrical in configuration, and is bounded by an outer surface 20, an inner surface 21, as well as first and second end surfaces 22 and 23, respectively. Extending between the inner and outer surfaces 21 and 20 are coaxially aligned slots 24 and 25, there being one pair of slots 24—25 for each movable collet element 14.

The inner tube element 12 is also of cylindrical configuration, and is bounded by an outer surface 28, an inner surface 29, which is at least partially threaded at 29a, and first and second end surfaces 30 and 31, respectively. A plurality of aligned bores 32 and 33 are positioned to correspond to the slots 24 and 25, and are engaged by pintles 34 preferably force fitted. The pintles are of length sufficient to extend outwardly of the slots 24 and 25, and engage the movable collet elements 14.

The threaded stud element 13 includes a shaft 37 having a hand wheel or adjusting knob 38 on the outer end thereof. The threaded member 39 engages the threaded portion 29a of the inner tube element 12 to impart motion thereto. The outer surface of the shaft 37 is provided with a suitable anti-friction bearing 40 capable of withstanding thrust when the device has been expanded to resiliently engage a cloth roll, generally indicated by reference character 41.

The movable collet elements 14 are substantially similar, and accordingly a detailed description of one of said elements will serve to describe all. Each includes a cylindrical member 44 bounded by end surfaces 45 and 46, an outer surface 47 and an inner surface 48 corresponding in diameter to the outer surface 20 of the outer tube element 11. Extending transversely with respect to the principal axis of the element 14 are aligned bores 49 and 50 which are engaged by the pintles 34 for the transmission of motion therethrough. A rabbeted surface 51 supports a cylindrical collar 52 to retain the spring members 16 therebetween.

The fixed collet elements 15 are also substantially similar, each including a cylindrical member 55 bounded by end surfaces 56 and 57, an outer surface 58, and an inner surface 59. Extending transversely between the outer surface 58 and inner surface 59 is a threaded bore 60 engaged by a set screw 61, the inner end of which bears upon the outer surface 20 of the outer tube element 11. A rabbeted surface 62 supports a cylindrical collar 63.

The spring members 16 are of an elongated flat type, and preferably three or more in number for each pair of movable and fixed collet elements 14 and 15. The spring elements each include first and second ends 66 and 67 at the terminals of a bowed arcuate portion 68, and are engaged beneath the collars 52 and 63 as best seen in FIGURE 3 in the drawing.

The sleeve element 17 is engaged upon one end of the outer tube element 11, and preferably adjacent the hand wheel or knob 38. It includes an inner surface 72, an outer surface 73 and a circular groove 74 permitting the engagement of the spindle with a corresponding means (not shown) for preventing axial movement of the device when in use, as is well-known in the art. The sleeve element 17 is preferably secured in position by means of a set screw 75.

In mounting a cloth roll 41 upon the spindle for rota-

tion, the knob 38 is first rotated with respect to the sleeve element 17 in a direction tending to move the movable collet elements 14 leftwardly as seen in FIGURES 1 and 3, wherein the spring members 16 are moved to a closer position with respect to the outer surface 20. In such position, the roll 41 may be easily slid from the leftwardmost end (FIGURE 1) to the desired axial position. Upon the rotating of the knob 38 in an opposite direction, the inner tube element 12 moves rightwardly as seen in FIGURE 2, resulting in transmitting motion through the pintles 34 and shifting the movable collet elements 14 rightwardly to bow the spring members 16 wherein the outer surfaces thereof will exert a resilient force against the inner surface of the cloth roll 41. Continued tightening movement will, within reasonable limits, not damage either the spindle or the cloth roll, but will merely result in exerting more resilient force against the cloth roll 41 to firmly grip the same.

I wish it to be understood that I do not consider the invention limited to the precise details of structure shown and set forth in this specification, for obvious modifications will occur to those skilled in the art to which the invention pertains.

I claim:

1. In an adjustable spindle for supporting a roll of web material thereon, an outer hollow tube element, an inner tube element slidably disposed within said outer tube element and having a hollow, at least partially threaded, bore therein, means for adjustably axially shifting said inner tube element with respect to said outer tube element, a plurality of first collet elements fixed upon the outer surface of said outer tube element, and a plurality of second collet elements slidably supported on said outer tube element for axial movement therealong, means interconnecting said second collet elements and said inner tube element for coextensive movement, and a plurality of elongated expandable spring elements interconnecting said

5 first and second collet elements and overlying said outer tube element; whereby relative movement between said first and second collet elements may serve to enlarge the effective diameter of said outer tube element at a plurality of areas spaced along said outer tube element to a substantially equal degree.

2. In an adjustable spindle for supporting a roll of web material thereon, an outer hollow tube element, an inner tube element slidably disposed within said outer tube element and having a hollow, at least partially threaded, bore therein, means for adjustably axially shifting said inner tube element with respect to said outer tube element, a plurality of first collet elements fixed upon the outer surface of said outer tube element, and a plurality of second collet elements slidably supported on said outer tube element for axial movement therealong, means interconnecting said second collet elements and said inner tube element for coextensive movement, each of the adjacently positioned first and second collet elements having a plurality of expandable spring elements disposed therebetween at substantially equally spaced angular intervals on the outer surface of said outer tube element; whereby relative movement between said first and second collet elements may serve to enlarge the effective diameter of said outer tube element at a plurality of areas spaced along said outer tube element to a substantially equal degree.
